[57] **CLAIM**

The ornamental design for a chair or seat end frame
component, as shown and described.

DESCRIPTION

FIG. 1 is a perspective view from the inner side of a
chair or seat end frame component embodying my new
design;

FIG. 2 is a top plan view thereof;
FIG. 3 is a side elevation view thereof;
FIG. 4 is a rear elevation view thereof; and
FIG. 5 is a front elevation view thereof.
